REMOTE CONTROL SYSTEM

Clarence S. Snavely, Pittsburgh, Pa., assignor to
The Union Switch & Signal Company, Swiss-
vale, Pa., a corporation of Pennsylvania

Application July 19, 1938, Serial No. 219,978

12 Claims. (Cl. 177—353)

My invention relates to remote control systems, for the control and indication of a large number of devices from a control point, and is particularly adapted for use in centralized traffic control systems for railroads, of the type in which traffic governing devices along a trackway are controlled from a train dispatcher's office, and the conditions of such devices and associated devices are indicated in such office, by the transmission of code signals transmitted over line wires extending from the dispatcher's office along the trackway to each field station in turn. More particularly, my invention relates to the line circuits for systems of this character, and has for an object the provision of improved means for transmitting the code signals with a minimum of distortion over distances greater than heretofore contemplated, particularly when the line circuits are in the form of cable having relatively small conductors and high electrostatic capacity. A further object is the provision of line circuits in which induced voltages from external sources will be neutralized to a large extent and will not interfere with the proper operation of the system.

One feature of my invention is the provision of suitable repeater stations by means of which the code signals may be repeated from one circuit to another as often as required.

Other objects and features of my invention will become apparent as the description proceeds.

It is to be understood that the centralized traffic control system embodying my invention includes apparatus at the control station, or dispatcher's office, for generating different series of code impulses arranged in distinctive combinations, each such series constituting a code message for selecting and controlling apparatus at a particular remote station, and that each remote station is provided with apparatus which is generally similar to that at the control office and which when initiated will operate through a cycle to transmit a combination of code impulses for indicating at the office the station of origin and the condition of devices at such station. My invention is not restricted to the use of code generating and receiving apparatus of a specific form, but may be used with any suitable system. In the specific embodiment of my invention herein illustrated, however, I have used apparatus for generating and receiving codes which is similar to that of the "Time code" scheme of Centralized Traffic Control as disclosed and claimed in a copending application, Serial No. 600,786, filed March 23, 1932, by Lloyd V.

Lewis, for Remote control systems, which corresponds with British Patent No. 415,787, issued September 3, 1934. The apparatus of my invention in the specific form shown herein is an improvement upon the line circuit portions of the apparatus of the said Lewis application and patent.

I shall first describe one form of apparatus embodying my invention, and shall then point out the novel features thereof in claims.

In the accompanying drawings, Fig. 1 is a diagrammatic view illustrating typical portions of the line circuits of my invention, including the apparatus directly associated with the line circuits at the control office, at a repeater station, and at a field station. Figs. 2 and 3 illustrate the local coding apparatus at the control office and at a field station, respectively, this apparatus being generally similar to the corresponding portions of the Lewis system above referred to. Fig. 4 is a single line diagram which illustrates one manner in which the line circuits of my invention may be arranged to control apparatus situated along an extensive stretch of railway track, of which only the two end portions are shown. It is to be understood that in Fig. 4, the apparatus identified by the reference "O" corresponds to the office equipment of Figs. 1 and 2, that identified by the references R—1, R—2, R—3, etc., each corresponds to that of a repeater station such as is shown in Fig. 1, and that the apparatus identified by the references S—1, S—2, S—34 and S—35, respectively, each corresponds to the station equipment of Figs. 1 and 3. It is also to be understood that in Fig. 4, each station equipment is employed to control the track switch W and the associated signals at one end of a passing siding by codes transmitted from the control office and to indicate the condition of the switch and signals and the presence of trains on the adjacent tracks as explained in the Lewis application, and that the arrangement shown is merely typical and may be varied as required in accordance with the track layout.

Similar reference characters refer to similar parts in each of the several views.

In the Lewis system hereinbefore referred to, a single normally closed line circuit extends from the office through each station in turn, and is energized by a battery at the control office. This circuit is interrupted repeatedly at varying time spaced intervals to form codes, and the periods of open circuit and closed circuit are both regulated so that both of these periods are employed as code elements. The apparatus is so consti-

tuted that the transmitter at the office or at a field station can initiate a code only when the line is free, and includes suitable provisions for preventing interference in the event the office and a station, or two stations, initiate transmission at the same time. When this occurs, the several codes are transmitted one at a time in order, the office taking precedence over the stations and each station taking precedence over those stations more remote from the control office.

The apparatus of my invention is distinguished by the employment of two normally closed line circuits in place of the single line circuit of the Lewis application. One of these is energized by battery at the office end and is utilized for the transmission of control codes from the office to the several field stations, while the other is normally energized by battery at the distant end, and serves as a communication channel for the transmission of indication codes from any field station to the office. Each line circuit has an auxiliary function, which comes into play when the other line circuit is in use, which is to "lock out" the transmitting apparatus at stations which have codes to transmit, so as to prevent interference with the station which is transmitting a code. Furthermore, my line signals are characterized by reversals of polarity as distinguished from closed and open intervals. As will be apparent from Fig. 1, the codes are delivered to the line circuit by the operation of pole-changer contacts, and are received by line relays R, each of which, it is to be understood, is of the two-position polarized type, so arranged that its contacts will remain in their last operated position when the relay is deenergized. Each line circuit used for code transmission also includes at its battery end, a checking relay K of the neutral type, (a biased polar relay may also be used) each relay K becoming released to prevent further code transmission when the corresponding line circuit is opened, but remaining picked up during the operation of the associated pole changer during code transmission.

In order to simplify the disclosure and to enable the circuits to be more readily understood, they have been arranged in the written circuit form, with similar circuits grouped together, but with relay contacts in many instances at points on the drawings not adjacent the relay winding which operates them. In every such case I have applied to the contact the reference character for the relay which operates it, and in addition, a separate reference character, a, b, c, etc., identifying the contact. Furthermore, instead of showing the local source of current for energizing the relays, I have shown only the terminals which are designated by the reference characters B and C, referred to the positive or supply terminal and to the negative or common return terminal, respectively, of the source.

Relays having corresponding functions at the office and stations are indicated by corresponding reference characters, the office relays being distinguished by the prefix "O", in each case.

Referring to Fig. 1, the relay OM is the "master relay" of the office coding unit, and is energized only for the duration of a control code and governs the transmission of such code, while relay OT is the transmitting relay which by the operation of its pole-changing contacts b and d delivers the control codes to the control line circuit. The first section of the control line circuit may be traced from the left-hand or positive

terminal of battery 9, at the office, back contact h of relay OM, left-hand contact a of the indication line relay IR, the upper winding of the control line relay OR, line wire X1, the windings of relay R1 and contact a of relay K1 at the repeater station, line wire X2, the lower winding of relay OR, contacts b of relays IR and OM, the winding of relay OK, to the right-hand terminal of battery 9. Similarly, the second section of the control line circuit may be traced from battery 10 at the repeater station through the winding of relay K1 and the pole-changer contacts a and b of relay R1, line wires X3 and X4, the station line relay R, being completed through a loop X5 at the remote end of the line. Normally, the polarity of the current delivered by battery 9 over the back contacts of relay OM is such as to operate the contacts of relays OR and R1 to the left, and the latter relay delivers current from battery 10 to line wires X3 and X4 to operate the contacts of relay R to the left.

The first section of the indication line circuit may be traced from a battery 11 at the distant end, over back contacts b and h of the station master relay M, line wires Y3 and Y4, front contact a of relay K2 and back contact a of a slow acting repeater relay K2P in multiple, the circuit being completed through the windings of the repeating line relay R2. The polarity of battery 11 is such that relay R2 operates its contacts to the left as shown.

The second section of the indication line circuit includes the battery 12, the winding of relay K2 and the pole-changer contacts a and b of relay R2 at the repeater station, line wires Y1 and Y2, the indication line relay IR, back contact j of relay OM and front contact b of relay OK at the office. The contacts of relay IR are normally held to the left, as shown, and therefore maintain normal polarity on the control line circuit.

The purpose of the line battery 11 is to maintain relays R2 and IR energized in their normal position when the equipment is at rest. When an indication code is initiated, however, relay M at the transmitting station picks up and at its contacts b and h disconnects battery 11 and connects a local battery 12 over the pole-changer contacts b and d of the associated transmitted relay T to that portion of the indication line which extends toward the office, this portion including the winding of a checking relay K at the station.

It will be apparent from the drawings that a failure of either section of the control line will cause relay OK to release and open, at its contact a, the local circuits controlled thereby, which as hereinafter pointed out, will prevent the delivery of a control code to an open line. Relay OK, at its contact b, at the same time opens the indication line. The latter is also opened at back contact j of relay OM whenever a control code is being transmitted. As hereinafter explained, the opening of the indication line prevents the delivery of an indication code by any field station.

It will also be apparent from the drawings that additional repeater stations or field stations may be connected into the line circuits at one or more points as desired, as indicated for example, by the specific arrangement illustrated in Fig. 4.

Referring now to Fig. 2, the "coding unit" therein illustrated is normally effective to respond selectively to indication codes delivered by the several field stations, and is rendered effective to deliver control codes to the control line and to simultaneously register such codes by the

operation of its line relay OR, in response to the energization of relay OM. Each control code delivered to the line comprises fourteen steps of alternate normal and reverse polarity. The first step is relatively long and serves to distinguish a control code from an indication code. Steps two to seven, inclusive, are arranged in different combinations of three long and four short impulses to provide thirty-five combinations for station selection. Steps eight to thirteen, inclusive, provide controls for five devices at the selected station, and the final or fourteenth step, operates the selected devices in accordance with the code and constitutes the return of the control line circuit to normal. Each indication code received at the office comprises sixteen steps, of which the first is relatively short and steps two to seven are arranged in a combination of three long and four short to identify the transmitting station. Steps eight to fifteen, inclusive, indicate the conditions of seven devices at the selected station, while the sixteenth step operates the indication devices of a corresponding panel at the office in accordance with the code and constitutes the return of the indication line circuit to normal. The successive steps of the code are "counted" by a series of stepping relays, O1 to O8, inclusive. The reception of a long impulse of normal or reverse polarity is manifested by the release of a slow acting relay OL2 or OL1, respectively.

In order to simplify the drawings and description, I have omitted a number of details of the complete apparatus, and shown only those parts which function during the transmission of a particular code, which may be identified as code No. 234, signifying that steps one to four, inclusive, are long and that steps five to eight, inclusive, are short steps. For simplicity, the remaining steps of the code are also assumed to be short steps.

I shall now briefly describe those operations of the office coding unit of Fig. 2 which take place in order to deliver this code to the control line circuit, assuming the line circuit to be normal, relays OR and OM being energized as shown and all the local relays of Fig. 2 being deenergized.

To initiate the code, the operator presses an individual starting key SK to pick up the corresponding starting relay 234, and contact e of that relay, completes a pick-up circuit for relay OM. As shown in Fig. 1, the contacts b and h of relay OM connect the pole-changer contacts b and d of the office transmitter relay OT into the control line in place of the contacts of relay IR, and relay OM at its contact j opens the indication line circuit. At contact e, relay OM completes a pick-up circuit for OT from terminal B at back contact a of relay OLBP over back contacts c of relays O3, O5, and O7, and relay OT picks up and reverses the polarity of the current delivered to the control line circuit, causing relay OR to close its right-hand contact a. As may readily be traced from the drawings, circuits are thereby completed to pick up relays OL1, O1, OL2, OLP, OLB and OLBP, successively in that order. Relays OLB and OLBP remain picked up for the duration of the code, relay OLB providing a stick circuit for OM. Relay O1, at its front contact c, completes a pick-up circuit for relay OE, and that relay and its repeater MEP pick up. The pick-up circuit for relay OT is now open, but relay OT is held energized over a stick circuit from terminal B over back contact g of relay OSP, front contact f of relay O1, front contacts d

and a of relays OL1 and OLP, in multiple, contact a of relay OT, contact c of relay OM, relay OT to terminal C. Relay OL1 became deenergized when OL2 picked up to open its back contact f, and relays OL1, OLP and OT now release successively to measure the first "long" step of the code.

The release of relay OT restores the polarity of the control line to normal, so that contact a of relay OR closes at the left. Relays O2 and OL1 pick up, and relay O1 releases. Although the release of relay O1 completes at its back contact c the pick-up circuit for relay OT, that relay is now short-circuited and consequently held in its released position to prolong the second step of the code by a connection from terminal B over front contact c of relay 234, back contacts j of relays 23G and 2F, front contact a of relay MEP, contact c of relay O2, contact f of relay OM, contact c of relay OT, to the left-hand terminal of the winding of relay OT. The slow-release relay OL2 is now deenergized, and when it releases, a circuit is completed from terminal B, front contact a of relay OLBP and back contacts of relays OCR, OLP, OL2 and OCR, front contact d of relay O2, front contact c of relay OE, the winding of relay 2F to terminal C. Relay 2F picks up and energizes relay OFP which picks up, releasing relays OE and MEP. Relay OT picks up to terminate the second step when back contact j of relay 2F opens.

Relay OT upon picking up again reverses the polarity of the control line, so that relay OR moves its contact a to the right. Relays O3 and OL2 now pick up and O2 releases. The pick-up circuit for OT is opened at back contact c of relay O3, but relay OT is held energized to prolong the third step by a connection from terminal B, over front contact c of relay 234, front contact j of relay 2F, and the front contact c of relay O3. Relay OL1 is now deenergized, and when it releases it completes a circuit at its back contact e to pick up relays 23G and OGP, and relay OGP causes relays 2F and OFP to release. Relay OT releases to terminate the third step when back contact j of relay 23G opens.

Relay OT upon releasing restores the polarity of the control line to normal, relay OR moves its contact a to the left, relays O4 and OL1 pick up and O3 releases. Although the pick-up circuit for relay OT closes, that relay is held released to prolong the fourth step by a connection from terminal B, front contact e of relay 234 and front contact j of relay 23G over contact c of relay O3 to the left-hand terminal of relay OT. Relays 234S and OSP pick up in response to the closing of back contact e of relay OL2, and then relays 23G, OGP and 234 release.

Relay OT picks up to reverse the polarity of the control line to begin the fifth step when the front contact j of relay 23G opens. On this step, relays O5 and OL2 pick up and O4 releases. The fifth step is short, because relay OT releases when back contact c of relay O5 opens, and begins the sixth step, during which relay O6 picks up and O5 releases. The sixth step is short, because relay OT becomes energized when back contact c of relay O5 closes. Each of the remaining steps of the code are short steps, for the reason that in the case described no further holding circuits for relay OT are closed and relay OT is governed solely by its pick-up circuit over the back contacts c of the stepping relays O1, O3, O5 and O7, which are controlled by relay OT through the medium of the line relay OR. The stepping is not terminated with the operation of relay O8 but relay O1

is operated next in order after O8, and picks up a chain repeat relay OCR on the ninth step, which completes a circuit at its contact *e* so that relay O2 picks up on the tenth step. Relays 5 O3 to O6 pick up successively on steps eleven to fourteen, and on step fourteen, relay OT is held released by a connection from terminal B over contact *f* of relay O6 to the left-hand terminal of relay OT, so that the line remains steadily energized by current of normal polarity.

This terminates the code, and relays OL2, OLP, OLB, OM and OLEBP release successively. Relay OLEBP opens the circuits for those relays of the coding unit which are energized, including relay 15 OL1, and the latter relay, upon releasing, closes its back contact *b* to condition the equipment for the transmission of another code.

Although steps nine to thirteen of the code have for simplicity been described as short steps, 20 it will be apparent from the drawings that any of these may be prolonged by completing a holding circuit for relay OT from terminal B over one of the front contacts *f* of the stepping relays O1 to O5.

25 I shall now describe the operation of the station coding unit of Fig. 3 in receiving the control code just described.

Relay R is, of course, operated by the code in the same manner as relay OR and the various 30 local relays controlled by relay R operate in the same manner as the corresponding relays at the office on each step of the code, with certain exceptions which will now be pointed out. It is to be understood that the station apparatus is 35 adapted to transmit codes as well as to receive them, the transmission of an indication code being initiated by picking up relay M over the circuit connected to terminal B at contact *c* of a starting relay ST, but this circuit is held open at 40 contact *b* of relay L1 or L2 when a control code is being received. Relays L1 and L2 pick up in unison with the office relays OL1 and OL2, at the beginning of the code. The indication line relay K, it will be remembered, was released by 45 the opening of back contact *j* of the office relay OM. It follows that when relay L1 picks up on the first step, a circuit is completed from terminal B over its front contact *c* and back contact *b* of relay K to pick up relay E. Relay E is held energized for the duration of the control 50 code, and opens its back contact *d* in the circuit for relay M. Since the pick-up circuits for relays M and OM are controlled independently, it may happen that an indication code will be initiated 55 by picking up the station relay M at the same time that the office relay OM picks up, but if this occurs, relay M will be released on the first step by the operation of relay E and the transmission of a conflicting indication code by the 60 station will be prevented, the station equipment being conditioned to receive the control code from the office by the operation of relay E. Relays F, G and S are connected to different front contacts *d* of the stepping relays at the different 65 stations in accordance with the code combination characteristics of the station. As shown in Fig. 3, these relays are connected to contacts *d* of relays 2, 3 and 4, respectively, so that this station as shown is responsive to the code No. 234 70 only. It follows that the station selector relay S will pick up only at the selected station illustrated in Fig. 3 when the office relay 234S picks up, but for any different code, one or more of the code steps 2, 3 or 4 will be short and the 75 selector relay S having the code combination

No. 234 will not pick up. At the selected station, a delivery relay D is picked up in place of the stepping relay 6 on the fourteenth step to control selected devices in accordance with the character of steps nine to thirteen of the code, but the circuits by which these devices are controlled have been omitted from the drawings since they have no bearing on the present invention.

I shall next assume that the apparatus has been restored to normal and that an indication 10 code is to be transmitted from the station of Fig. 3.

The indication code is initiated by picking up the starting relay ST by means not shown, either in response to a change in condition of one of 15 the station devices having indications to transmit, or following the receipt of a control code at the station. As already explained, relay ST at its contact *c* closes the pick-up circuit for relay M, which becomes energized and disconnects the 20 more remote stations from the indication line, and completes a circuit from the line battery 12 through relay K for temporarily maintaining relay R2 energized in its normal direction. Relays T and K now pick up, and relay T reverses the 25 polarity of the indication line for the first step of the indication code, reversing relay R2 at the repeater station, which in turn reverses the indication line relay IR at the office. Relay IR reverses the polarity of the control line, so that 30 relays OR and R1 reverse, and relay R1 reverses the control line relay R at the transmitting station.

When the relay R at each station is reversed, the associated relays L1, O1, L2, LP, LB and LBP 35 pick up, at the same time relay OR picks up the corresponding office relays as in the case of the control code already described. When relay LBP at the transmitting station picks up, a circuit is completed from terminal B over its front contact *f*, front contact *a* of relay K to pick up relay KP, which relay is held energized for the duration of the code over its own front contact *a* and back contact *g* of relay E, provided relay E remains deenergized. Relay KP by the operation of its contact *b* places the local relays of 45 Fig. 3 at the sending station under the control of contact *e* of relay T in place of contact *a* of the line relay R, for the remainder of the indication code.

It has already been pointed out that the station relay E will pick up if relays OM and M should happen to pick up at the same time, in which case the office will take precedence over the station. Assuming that this does not occur, it will be seen from Fig. 2 that relay OM 55 can not pick up later to interfere with the indication code, because its pick-up circuit will be open at back contact *b* of relay OL1 or OL2 controlled by relay OR until the code is completed. No other field station can interfere with the indication code after it is started, for the reason that the pick-up circuit for each relay M is similarly held open by relay L1 or L2 controlled by the corresponding relay R, while the 60 relay M at the sending station only, is held energized over its stick circuit.

It may happen, however, that two or more stations start transmitting at the identical moment so that the stick circuits for more than 70 one relay M are completed. In this case, it will be clear from Fig. 1 that the portion of the indication line circuit extending from the transmitting station nearer the office to the more remote stations will be open at back contacts *b* 75

and *h* of relay M at the station nearer the office, or at contact *a* of relay K2, if there is a repeater between such nearer station and the more remote stations. Relay K at each more remote station consequently will release and complete at its contact *b* a pick-up circuit for relay E at such station, and each such relay E at its back contacts *d* and *e* will open the circuits for relays M and KP, respectively, at the corresponding station, to restore the apparatus to the receiving condition. It will be clear therefore that but one station can transmit a code at a time.

As above pointed out, the control of the stepping relays and of relay L1, L2, etc., is transferred from the line relay R to relay T at the transmitting station by relay KP when relay LBP picks up. Relay LBP also opens the pickup circuit for relay T at its back contact *a* so that relay T releases to terminate the first step of the indication code shortly after relay KP picks up, restoring the polarity of the line circuits to normal and also picking up relays 2 and L2. Relay 1 releases, and closes the pick-up circuit for relay T, but that relay is prevented from picking up because terminal B is now connected to its left-hand terminal over a circuit including back contact *b* of relay F. Relay L1 is now deenergized, and when it releases, it closes a circuit at its back contact *e* to pick up relay F, permitting relay T to pick up to terminate the second step. This action, it will be seen, is similar to that already described in connection with the transmission of a control code by the equipment of Fig. 2. The action on the remaining steps is also similar, that is, relays G and S pick up on the third and fourth steps, in response to the release of relays L2 and L1 respectively, and control the holding circuits for relay T to prolong these steps of the code, while on the remaining steps of the code relay T is controlled only by its pick-up circuit including back contacts *c* of the stepping relays 1, 3, 5 and 7 so that these are short steps, in the code described. Relay 1 picks up on the ninth step next in order after relay 8, and energizes relay CR to prepare a circuit for relay 2, and relays 2 to 7, inclusive, are operated on steps nine to fifteen, respectively, relay 16 being operated in place of relay 8 when the indication line becomes steadily energized by current of normal polarity at the end of the code. Relay 16 at its back contact *c* deenergizes relay M, and also picks up a relay VP which at its front contact *e* connects terminal B to the left-hand terminal of relay T to prevent further operation of that relay, and therefore relays M, L2, LP, LB, LBP, L1 release successively. The release of relay M places the indication line under the control of battery 11, restoring the line circuits to normal and releasing relay K. Relay LBP releases the remaining local relays, as in the case of the office equipment already described.

It is believed that the manner in which this indication code is received at the office in response to the operation of the line relay OR will be apparent without further description in view of the detailed description of the operation of that equipment already given, and that it will be clear that the selector relay 234S will be operated selectively in response to the transmitted code No. 234.

It will also be evident that the equipments at the other field stations will also be operated at the same time, but since none of these stations respond to code No. 234 the corresponding relays S at such stations will not be operated.

Returning now to Fig. 1, it is believed that in

view of the foregoing description it is clear that additional field stations may be included in series in the line circuit to any extent desired, up to the maximum capacity of the system, and that repeater stations may be added in series at any point, in accordance with the practical requirements of a particular installation, without changing the mode of operation in any way, and that my apparatus is adapted for use under a wide variety of conditions and is particularly adapted to provide reliable transmission over long distances and under adverse conditions. In practice, the most remote station may be several hundred miles from the dispatcher's office, and the line conductors may be either open wires or relatively small conductors enclosed in cable, without materially impairing the quality of transmission as compared with a short line.

Certain features of Fig. 1 will now be explained. It will be noted that relay K2 at the repeater station at its front contact *f* controls a slow acting repeater relay K2P. When the indication line is opened by relay OM, at the beginning of a control code, releasing relay K2, relay K2P becomes deenergized and after a brief time interval releases to reestablish the continuity of the remote section of the indication line at its back contact *a*. This results in maintaining the repeater station line relay R2 energized in its normal direction, so that when back contact *f* of relay OM closes at the end of the control code, relay IR at the office will immediately become energized in the normal direction to supply current of normal polarity to the control line over its contacts *a* and *b*. Otherwise it might occur that an extra impulse of reverse polarity would be transmitted over the control line at the end of a control code.

The purpose of the office relay OK in the control line is to prevent coding in case the control line becomes open. In case the line is in a cable, the transient charging currents produced by the repeated reversal of the line battery 9 by the pole-changer contacts of relay OT may be sufficient to operate line relay OR, even though the line is open at its distant end. Since relay OR is of the stick polar type, its contacts remain in their last operated position even though the flow of current through its windings ceases, so that, as far as relay OR is concerned, a control code once started may continue even though the line is open. This is prevented, however, by relay OK, which requires a continuous flow of line current to hold it picked up, and will release if the control line opens. Relay OK upon releasing will open the local coding circuits at its contact *a* and thereby prevent further transmission until the line is restored.

One advantage of the transmission system of the present application is that the line relays are held in their operated positions substantially continuously by the current delivered to the line by the transmitter, and are therefore less subject to interference than when the coding is effected by merely opening and closing the line, and the line relays are arranged with balanced windings so as to be immune to a large degree to induced currents due to foreign sources. A further advantage is that the so-called "bias distortion" of the code signals is avoided. This term refers to a lack of symmetry in the wave form of the received code signals which may exist when the signals are produced by opening and closing a long cable line circuit, or in case appreciable leakage of line current exists due to weather conditions. As is well known, the trans-

mission of code signals over extremely long distances and under adverse conditions can best be effected by merely pole-changing the line current, as employed in the system of the present application. Furthermore, since each line circuit of the present system is used for transmission in but one direction only, repeaters may be added without complication, as has already been pointed out, and the line circuits may be controlled by a plurality of independent transmitters without interference even though the transmitting stations are widely separated.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In a remote control system, an office and a plurality of stations, a control line and an indication line connecting the office and stations, a code transmitter at the office effective when initiated to transmit a multiple impulse control code over said control line, a code transmitter at each station effective when initiated to transmit a multiple impulse indication code over said indication line, a repeating relay at the office having its winding included in said indication line and its contacts in said control line for repeating over the control line each indication code transmitted over the indication line, code responsive means at the office and at each station responsive to codes transmitted over the control line, and lock-out means associated with each code-responsive means for preventing the operation of the associated code transmitter as long as a code is being transmitted over the control line by another transmitter.

2. In a remote control system, a transmitting station and a receiving station, a normally energized line circuit including a source of current, and a pole-changer at the transmitting station; a neutral relay in said line circuit between said source and said pole-changer, a two-position polar line relay at the receiving station controlled in accordance with the polarity of the current supplied to said line circuit, means at the transmitting station effective only when said neutral relay is picked up by current delivered to said line circuit from said source for operating said pole-changer to reverse the polarity of the current supplied by said source at time-spaced intervals of variable length to operate said line relay in accordance with different codes, and code receiving means controlled by said line relay and selectively responsive to the relative lengths of said intervals in said codes.

3. In a remote control system, a transmitting station and a receiving station, a normally energized line circuit including a source of current and a pole-changer at the transmitting station; a neutral relay in said line circuit between said source and said pole-changer, a two-position polar line relay at the receiving station controlled in accordance with the polarity of the current supplied to said line circuit, means at the transmitting station effective only when said neutral relay is picked up by current delivered to said line circuit from said source for operating said pole-changer to reverse the polarity of the current supplied by said source at time-spaced intervals of variable length to operate said line

relay in accordance with different codes, code receiving means controlled by said line relay and selectively responsive to the relative lengths of said intervals in said codes, and means at said receiving station for opening said line circuit to prevent the operation of said pole-changer.

4. In a remote control system, a control station, a repeater station and a remote station, a normally energized control line having a first portion including a source of current, a first neutral relay and a pole-changer at the control station, and also including a two-position polar line relay at the repeater station, said line having a second portion including a source of current, a second neutral relay and a pole-changer controlled by the line relay at said repeater station and also including a two-position polar line relay at the remote station, means effective only when the first neutral relay is picked up for operating the pole-changer at the control station to periodically reverse the polarity of the current supplied to said first section to operate said line relays in accordance with different codes, and means controlled by the second neutral relay for opening the first section of the line circuit to prevent the operation of the pole-changer at the control station in the event the second section of the line circuit is opened.

5. In a remote control system, a control station and a remote station, a line circuit including a source of current and a polarized line relay at the control station, a second polarized line relay at the remote station controlled in accordance with the relative polarity of energization of said line circuit, a master relay at the control station, a first code transmitter at the control station controlled from a remote point and effective only when said master relay is deenergized to deliver codes of time spaced impulses of alternately opposite polarity and of variable length to said line circuit, a second code transmitter at the control station effective only when said master relay is energized to deliver different codes of time spaced impulses of alternately opposite polarity and of variable length to said line circuit, code responsive means at each station selectively responsive to the relative lengths of the impulses of the codes received by said line relays, and starting means at the control station for energizing said master relay effective only when said first code transmitter is not in operation.

6. In a remote control system, a control station and a remote station, a normally closed line circuit including a source of current and a polarized line relay at the control station, a second polarized line relay at the remote station controlled in accordance with the relative polarity of energization of said line circuit, a master relay at the control station, a first code transmitter at the control station controlled from a remote point and effective only when said master relay is deenergized to deliver codes of time spaced impulses of alternately opposite polarity and of variable length to said line circuit, a second code transmitter at the control station effective only when said master relay is energized to deliver different codes of time spaced impulses of alternately opposite polarity and of variable length to said line circuit, code responsive means at each station selectively responsive to the relative lengths of the impulses of the codes received by said line relays, starting means at the control station for energizing said master relay effec-

- tive only when said first code transmitter is not in operation, and means for preventing the operation of either code transmitter when said line circuit is open.
5. In a remote control system, an office and a station, a normally closed line circuit including at the office a single current source and a first two-position polar line relay, a second two-position polar line relay at said station controlled in accordance with the relative polarity of the current supplied to said line circuit, a first and a second pole-changer at the office each effective when operated to reverse the polarity of the line current from said source at time spaced intervals to produce a code, code receivers at the office and station each selectively responsive in accordance with the relative time spacing of successive operations of the associated line relay, means at the office for operating the first pole-changer repeatedly at selected time intervals of different lengths to deliver a code to the line circuit to which the station code receiver is responsive, and means at the station for operating the second pole-changer repeatedly at selected time intervals of different lengths to deliver a code to the line circuit to which the office code receiver is responsive.
8. In a remote control system, a control line including a plurality of normally closed circuit portions, each including a two-position polar line relay at one end and a pole-changer and a source of current at the other end, a neutral relay in each portion between the pole-changer and source of current, code transmitting means at a control station for controlling the pole-changer for the first portion to deliver a code of time spaced reversals of current to said line, means controlled by the line relay for each except the last portion for controlling the pole-changer for the next succeeding portion to repeat said code, code responsive means controlled by the line relay for the last portion, and means including said neutral relays effective to stop the operation of the transmitting means in the event any one of said circuit portions becomes opened.
45. 9. In a remote control system, two stations connected by a normally closed line circuit including a source of current at one station, a pole-changer at one station effective when actuated to reverse the polarity of the current delivered to said line circuit, a series of stepping relays, means controlled by said pole-changer for operating said stepping relays one at a time in order, one for each actuation of said pole-changer, means responsive to each successive operation of a stepping relay for actuating said pole-changer to thereby deliver a series of relatively short impulses of alternately opposite polarity to said line circuit, means at said one station controlled in accordance with a code for delaying the operation of the pole-changer when selected stepping relays are operated to prolong selected impulses of said series, and code responsive means at the other station selectively responsive to the relative lengths of the impulses of said series irrespective of their polarity.
10. In a remote control system, two stations connected by a normally closed line circuit including a source of current at one station, a pole-changer at one station effective when actuated to reverse the polarity of the current delivered to said line circuit, a series of stepping relays, means controlled by said pole-changer for operating said stepping relays one at a time in order, one for each actuation of said pole-changer, means responsive to each successive operation of a stepping relay to deliver a series of impulses of alternately opposite polarity to said line circuit, time controlled means for delaying the actuation of said pole-changer to prolong selected impulses of the series, means at said one station for selectively controlling said time controlled means in accordance with a code, and code responsive means at the other station selectively responsive to the relative lengths of the impulses of said series irrespective of their polarity.
11. In a remote control system, two stations connected by a first and a second line circuit, a series of stepping relays at each station, means for operating the relays of each series sequentially when impulses of alternately opposite polarity are transmitted over said first line circuit, a code transmitting relay at one station for transmitting impulses of alternately opposite polarity over said first line circuit, a code transmitter at the other station for transmitting impulses of alternately opposite polarity over said second line circuit, means at said one station for retransmitting over said first line circuit the impulses received over said second line circuit means at each station controlled by the stepping relays at that station for at times operating the associated code transmitter and for governing the relative lengths of the impulses transmitted over the corresponding line circuit to the other station in accordance with a code, code responsive means controlled by each series of stepping relays selectively responsive to the relative lengths of the impulses of the code delivered by the other station, independent means for initiating the operation of said code transmitters, and means at one station for discontinuing the operation of the code transmitter at that station in the event the operation of the other transmitter has been initiated.
12. In a remote control system, an office and a plurality of stations, line wires connecting the office and stations to provide a control line channel and an indication line channel, a code transmitter at the office effective when initiated to transmit a multiple impulse control code to the stations over the control line channel, a code transmitter at each station effective when initiated to transmit a multiple impulse indication code to the office over the indication line channel, a repeating relay controlled over the indication line channel having contacts in the control line channel for repeating over the control line channel each indication code transmitted over the indication line channel, code responsive means at each station selectively responsive to codes transmitted from the office, code transmitting means at the office selectively responsive to codes transmitted from the stations, and means for initiating the operation of each transmitter effective only when there is no code being transmitted over the control line channel.
